UNITED STATES PATENT OFFICE.

GEORGE H. DAWSON, OF CAMBRIDGE, MASSACHUSETTS, ASSIGNOR TO LIBRARY
BUREAU, A CORPORATION OF NEW JERSEY.

CARD OR SHEET PROTECTOR.

Application filed December 5, 1921. Serial No. 520,186.

To all whom it may concern:

Be it known that I, GEORGE H. DAWSON, a citizen of the United States, and a resident of the city of Cambridge, in the county of Middlesex and State of Massachusetts, have invented certain new and useful Improvements in Card or Sheet Protectors; and I do hereby declare that the following is a full, clear, and exact description of the same, reference being had to the accompanying drawings, and to the numerals of referring marked thereon, which form a part of this specification.

This invention relates to a transparent protective sheet such as celluloid or mica or the like for covering the data or written matter upon index cards or the like, which are adapted to be used in a card index system and mounted in a tray in overlapping relation with their lower edges exposed.

In the past it has been customary to cover merely the exposed edges of the cards by transparent strips interlocked therewith by mutilating the lower corners of the cards or by attaching the same by eyelets or the like. There are many obvious objections to mutilating the lower edges of the cards especially when the same is typed, besides the necessary labor and time that is lost in removing the protective strips when necessary. Further, the data on the cards above the transparent strip is not protected from dirt that gathers between the overlapped cards. It is the purpose of my invention to overcome these objections.

It is therefore an object of this invention to provide a transparent protective sheet that covers substantially the entire front face of the card and that is not directly attached to the card, but is provided with means for frictionally engaging said card.

It is a further object of this invention to support the protective sheet in combination with the card so that the protective sheet may be readily dissociated with respect to the card when the latter is removed from its support, so that any matter can be readily added to the index card.

With these and other objects in view which will become more apparent in the following description, my invention comprises the novel structure and arrangement hereinafter described and more particularly

pointed out and defined in the appended claims.

In the accompanying drawing which illustrates a preferred embodiment of my invention and in which similar reference numerals refer to similar features in the different views:

Figure 1 is a front view of a card mounted upon its support and covered by my protective sheet.

Figure 2 is an end view thereof.

Figure 3 is a plan view of the protective sheet detached from its support.

Figure 4 is an edge view of the protector with the card in place beneath the same, upon an enlarged scale.

Figure 5 is an enlarged edge view of the tension flange that presses the protector against the card.

In the different figures of the drawings, I have illustrated one embodiment of my invention which comprises a transparent sheet 1 having an edge portion 2, preferably the lower edge portion, bent to the rear and slightly inclined downwardly and an upwardly turned and slightly bowed-in tension flange 3 contacting the rear of the sheet. The particular construction is such that the flange 3 presses firmly against the back of the sheet 1 and draws the same against a card when the same is supported beneath the sheet and exerts sufficient friction to facilitate simultaneous mounting of the card and sheet upon the same support. The upper edges of the sheet 1 are provided with elongated notches 4 adapted to receive studs or eyelets 5 on a card support 6.

The card 7 which the transparent sheet 1 is designed to protect is likewise provided with a pair of similar elongated notches 8 adapted to receive the said studs or eyelets 5 and when the card 7 is placed beneath the sheet 1 with its lower edge inside the flange 3, the flange 3 will frictionally hold the card as shown in Figures 2 and 3, the notches in the card and sheet will coincide or be in alinement so that by slightly flexing the combined card and sheet, they can be simultaneously mounted upon the eyelets 5 as is obvious. And by a slight flexure, they can be also simultaneously removed as is evident. It is characteristic of my invention that the protective sheet 1 is always free

from the card and may be readily detached from its support without removing the card from its support, and may also be readily placed over the card after the same is mounted.

The card support 6 may comprise a fabric strip having flaps 8 extending inwardly at the upper edges and secured to the eyelets 5 for more effectively preventing lateral movement of the card and protective sheet; the fabric being secured to a rectangular spacing bar 9 which is adapted to fit in guide channels of a tray.

It will evidently be observed that I have invented a novel transparent protective sheet that covers the whole front face of the card, that is not attached to the card and that is provided with means for pressing the sheet against the card.

I am aware that numerous details of construction may be varied through a wide range without departing from the principles of this invention, and I therefore do not purpose limiting the patent granted otherwise than necessitated by the prior art.

I claim as my invention:

1. The combination with a card, of a support to which the card is removably secured,

and a transparent sheet removably mounted on said support and having means for 30 pressing itself against said card.

2. The combination with a card, of a support therefor comprising a pair of spaced studs having flaps thereon, a transparent sheet having notches adapted for engaging 35 said studs under said flaps for covering the card mounted on said support.

3. The combination with a card, of a support therefor having studs, and a transparent sheet for covering the front face of said 40 card, said card and sheet having notches adapted to be brought into alignment for simultaneously mounting them upon said studs by a flexing movement.

4. The combination with a card, of a 45 support to which the card is detachably secured, and a transparent sheet removably mounted on said support and having a flange embracing an edge of said card.

In testimony whereof I have hereunto 50 subscribed my name in the presence of two subscribing witnesses.

GEORGE H. DAWSON.
